US00D817120S

(12) **United States Design Patent** (10) Patent No.: **US D817,120 S**
Eich (45) Date of Patent: ** May 8, 2018

(54) **SPICE MILL NON ELECTRIC**

(71) Applicant: **Michael Eich**, Troinex (CH)

(72) Inventor: **Michael Eich**, Troinex (CH)

(**) Term: **15 Years**

(21) Appl. No.: **35/502,499**

(22) Filed: **Jan. 29, 2017**

(80) **Hague Agreement Data**

Int. Filing Date: **Jan. 29, 2017**

Int. Reg. No.: **DM/094733**

Int. Reg. Date: **Jan. 29, 2017**

Int. Reg. Pub. Date: **Feb. 24, 2017**

(51) **LOC (11) Cl.** **07-04**

(52) **U.S. Cl.**

USPC **D7/679**
